GAS METER HOUSING

Edward R. Gilmore, Little Rock, Ark., assignor to Arkla
Industries Inc., a corporation of Delaware

Filed Sept. 16, 1959, Ser. No. 57,576

Term of patent 14 years

(Cl. D52—6)

FIG. 3

FIG. 4

FIG. 1

FIG. 2

FIGURE 1 is a front elevation of a gas meter housing showing my new design.

FIGURE 2 is a side elevation of the gas meter housing of FIGURE 1;

FIGURE 3 is a top plan view of the gas meter housing of FIGURE 1;

FIGURE 4 is a rear elevation of the gas meter housing of FIGURE 1.

The side of the gas meter housing not shown in the drawing is the same in appearance as the side shown in FIGURE 2.

I claim:

The ornamental design for a gas meter housing, substantially as shown and described.
